UNITED STATES PATENT OFFICE

2,441,268

RESILIENT HOLDER FOR ABRASIVE AND
CLEANING MATERIALS

Charles L. Haber, New York, N. Y.

Application October 17, 1944, Serial No. 559,017

5 Claims. (Cl. 15—209)

1

This invention relates to improvements in devices for effectively holding scouring or scraping materials, such as steel wool.

A further object of this invention is the provision of an improved holder for grasping and supporting material such as steel wool in a hand protecting relation and in such manner that the steel wool may be most efficiently used for cleaning purposes.

A further object of this invention is the provision of an improved flexible type steel wool holder of such conformation that it may be grasped and held in the hand of a user with ease and under such circumstances that the steel wool will be most efficiently positioned for use.

Other objects and advantages of the invention will be apparent from the following detailed description.

In the accompanying drawing, forming a part of this specification, and wherein similar reference characters designate corresponding parts throughout the several views:

Figure 1 is a perspective view of the improved holder supporting a cluster of steel wool; the manner in which the holder is grasped being shown in dot and dash lines.

Figure 2 is a longitudinal cross sectional view thru the holder.

Figure 3 is a transverse sectional view taken substantially on the line 3—3 of Figure 2.

Figure 4 is a perspective view of the open end of the holder.

Figure 5 is a cross sectional view taken substantially on the line 5—5 of Figure 2.

Figure 6 is a modified form of supporting teeth in the holder.

In the drawing, wherein for the purpose of illustration are shown preferred and modified forms of the invention, the letter A may generally designate the improved holder. The material of which the holder is made is plastic, leather, rubber, textile, or any other material found suitable for use. In the main, the holder is in the form of an inverted pocket having the front and lower portions open for the reception of a cluster of steel wool or like abrasive material. The same includes a top wall 10, and side walls 11 and 12. The walls 11 and 12 have a general convergence, as shown in Figures 3 and 5 of the drawing, and at their lower edges they are provided with teeth or serrations 14 extending substantially the length of the holder from a point designated at 15 in Figure 2 of the drawing below the finger engaging depressed

2

pocket 17 to the point 18 designated in Figure 2 adjacent the rear palm receiving curved wall 20. These teeth 14 may be formed integral with the material. The teeth are rather rigid and adapted for the purpose of biting into and gripping the cluster of steel wool to prevent the shifting of the wool within the holder as the operator reciprocates the cluster for cleaning purposes. In the event the material used is plastic, the teeth 14 may be hardened in a manner conventionally understood by those skilled in the art, or the teeth may be of the form shown at 14a in Figure 6 molded into the hardened marginal portion 25 of the wall. If the flexible material used is rubber, the teeth, of course, are either of hard rubber or molded into the material.

The top wall 10 preferably bulges upward with both a longitudinal and transverse convexity.

20 Along the top wall there may be positioned axial ribs or corrugations, shown at 50, and on the under side the top wall is provided with a preferably rigid rib, which may be conveniently referred to as the backbone of the holder, and 25 designated at 31. The top wall of the holder is provided with the finger tip engaging depression 17; the material of the top wall at this depression 17 being flexible and the backbone or rib 31 extending continuous from the rear of 30 this depression thruout the length of the holder to the palm receiving curved back wall 20. The fore end of the holder may have an upwardly convexed lip 34 to prevent the steel wool from overlapping the top of the holder.

35 The side walls 11 and 12 are provided with thumb and finger receiving depressions 40, shown best in Figure 3 of the drawing; these depressions having their greatest depth at a point intermediate the ends of the holder and 40 gradually decreasing in depth towards the rear.

The manner of use of the holder will be apparent from the foregoing. The walls 11 and 12 are springy and pliable and the cluster of wool is positioned between them. The steel wool cluster fairly fills the interior pocket of the holder and the latter is then grasped in the hand of the user, in a manner such as shown in Figure 1; the index finger tip resting in the pocket 17 with the rear of the holder lying in the palm of the hand. The thumb engages in one side wall depression and the tips of the other fingers may engage in the depression of the other side wall. Thus the holder is shaped to be grasped and squeezed with facility. The 55 teeth of the holder will bite into the cluster of

steel wool to prevent its reciprocation within the holder and by pressure upon the top wall, the backbone or rib 31 will force the steel wool forwardly and downwardly so that it will always be in position to most efficiently perform the scouring or scraping operation. The bulging of the steel wool is an incident of the formation of the rib 31 in the position shown to most efficiently carry out the cleaning operation.

It is, of course, apparent that the holder may be grasped in either the right or the left hand of the user and full pressure may be used without liability of injury to the hand of the user. This is brought about because of the extreme length of the pocket and the formation of the curved flexible back wall which fits in the palm of the hand in a complete socketed relation in pressure contact with the carpus and metacarpus of the hand. Pressure is therefore relieved principally from the fingers and taken by the hand. This enables the user to apply body pressure without tiring the fingers or the hand.

In the specification and claims wherever the words "steel wool" are used it is the intention that the holder may receive any suitable abrasive cleaning material likely to injure the hands, in substitution of steel wool, for the purpose defined.

Various changes in the shape, size and arrangement of parts may be made to the form of invention herein shown and described, without departing from the spirit of the invention or the scope of the following claims.

I claim:

1. A flexible holder for cleaning material such as steel wool comprising a flexible top wall and depending flexible side walls, the said walls defining a pocket for receiving a cluster of the steel wool or the like in bulging relation from the pocket, said top wall having a portion normally bulging into the pocket defining an exterior finger receiving depression on the top surface to facilitate grasping and operation of the holder.

2. A steel wool holder of the class described comprising a top wall shaped to receive the hand of a user having a flexible depressed finger engaging portion providing an external depression inwardly from the top thereof, depending flexible side walls having finger and thumb engaging depressions externally therein, said top and side walls providing a downwardly and forwardly opening pocket.

3. A holder of the class described comprising a top wall shaped to receive the hand of a user having a flexible finger engaging portion depending below the wall and having a depression inwardly from the top thereof, depending flexible side walls having finger and thumb engaging

depressions externally therein, said top and side walls providing a downwardly and forwardly opening pocket, and a substantially rigid backbone connected as a part of the top wall and axially depending into the pocket in spaced relation from the side walls.

4. In a holder for abrasive material such as steel wool the combination of a top wall structure of elongated formation having depending flexible side walls, said top wall structure including a downwardly curved back wall adapted to seat in the palm of the hand of the wearer, the walls defining a pocket for receiving the steel wool which opens downwardly and also forwardly, said side walls internally thereof having wool engaging projections, and the top wall forwardly thereof having an index finger receiving depression defining a protuberance extending into the pocket for normally bulging the steel wool into operating position.

5. A steel wool holder comprising a body portion defining a top wall shaped to fit in the palm of the hand of the user and of a length to permit the index finger of the user to rest upon the forepart thereof, said body portion having flexible depending side walls spaced at the lower margins thereof and together with the top wall defining a downwardly opening pocket for receiving steel wool, said side walls being of a nature to receive at one side wall the thumb of the hand of the user and at the other side the ends of the little, third and middle fingers of the user's hand, said body portion having the pocket thereof opening at the outer fore end so that steel wool will project at the front of the holder, and a rear sloping wall at the rear end thereof.

Certificate of Correction

May 11, 1948.

Patent No. 2,441,268.

CHARLES L. HABER

It is hereby certified that error appears in the printed specification of the above numbered patent requiring correction as follows: Column 3, line 40, claim 1, before the word "portion" insert *flexible*; and that the said Letters Patent should be read with this correction therein that the same may conform to the record of the case in the Patent Office.

Signed and sealed this 13th day of July, A. D. 1948.
